US00D862508S

(12) **United States Design Patent** (10) Patent No.: **US D862,508 S**
(45) Date of Patent: ** Oct. 8, 2019

(54) **DISPLAY SCREEN OR PORTION THEREOF
WITH GRAPHICAL USER INTERFACE**

(71) Applicant: **Apple Inc.**, Cupertino, CA (US)

(72) Inventors: **Patrick Lee Coffman**, San Francisco, CA (US); **Raymond Sepulveda**, San Jose, CA (US)

(73) Assignee: **Apple Inc.**, Cupertino, CA (US)

(**) Term: **15 Years**

(21) Appl. No.: **29/683,939**

(22) Filed: **Mar. 18, 2019**

Related U.S. Application Data

(63) Continuation of application No. 29/642,082, filed on Mar. 27, 2018, now Pat. No. Des. 849,780, which is a continuation of application No. 29/582,325, filed on Oct. 27, 2016, now Pat. No. Des. 815,140.

UNITED STATES PATENT AND TRADEMARK OFFICE
CERTIFICATE OF CORRECTION

PATENT NO. : D862,508 S
APPLICATION NO. : 29/683939
DATED : October 8, 2019
INVENTOR(S) : Patrick Lee Coffman et al.

Page 1 of 3

It is certified that error appears in the above-identified patent and that said Letters Patent is hereby corrected as shown below:

On the Title Page

Delete the title page and substitute therefore with the attached title page consisting of the corrected illustrative figure(s).

(57) DESCRIPTION

Below statement should be added to the beginning of the section:

-The file of this patent contains at least one drawing/photograph executed in color. Copies of this patent with color drawing(s)/photograph(s) will be provided by the Office upon request and payment of the necessary fee..-

Below statement should be added to the end of the section after “1 Claim, 1 Drawing Sheet”:

-(1 of 1 Drawing Sheet(s) Filed in Color)-

In the Drawings

Please replace sole figure with sole figure as shown on the attached page.

Signed and Sealed this
Seventh Day of January, 2020

Andrei Iancu
Director of the United States Patent and Trademark Office
